UNITED STATES PATENT OFFICE.

SAMUEL N. NORTH, OF MUNCIE, INDIANA.

SAFETY APPLIANCE FOR CONTAINERS.

1,118,573.

Specification of Letters Patent.

Patented Nov. 24, 1914.

Application filed December 22, 1911. Serial No. 667,401.

To all whom it may concern:

Be it known that I, SAMUEL N. NORTH, a citizen of the United States, residing at Muncie, in the county of Delaware and State of Indiana, have invented certain new and useful Improvements in Safety Appliances for Containers, of which the following is a specification.

This invention relates to improvements in safety appliances for the cans or other containers for gasoline or other hydro-carbon compounds or liquids, and has for one of its objects to provide a simply constructed device which will effectually prevent blazes from igniting the gases generated in the containers, and may be applied to cans or like containers of various kinds, automobile tanks, gasoline and stove tanks, reservoirs or other containers which are liable to come in direct contact with flames.

Another object of the invention is to simplify and improve the construction and increase the efficiency and utility of devices of this character.

Another object of the invention is to provide a device of this character which may be readily applied without structural change to cans or other containers of various sizes.

Another object of the invention is to provide a device of this character which may be readily removed when the can is to be filled and which does not interfere with the ordinary uses of the can or other container.

With these and other objects in view, the invention consists in certain novel features of construction as hereafter shown and described and then specifically pointed out in the claims.

The improved device may be applied to cans, automobile tanks, gasoline stove tanks, reservoirs or like containers, but is more particularly applicable to cans, and for the purpose of illustration is shown thus applied, and in the drawings employed to illustrate the preferred embodiment of the invention:

Figure 1 is a sectional elevation of a conventional can with the improvement applied; Fig. 2 is a plan view of the same; Fig. 3 is a transverse section on the line 3-3 of Fig. 1; Figs. 4 and 5 are views similar to Fig. 1 illustrating modifications in the construction.

Corresponding and like parts are referred to in the following description and indi-

cated in all the views of the drawings by the same reference characters.

The can to which the improved device is applied, is represented as a whole at 10 and is provided with the usual threaded nozzle 11, the nozzle extending outwardly as shown in Fig. 1, or turned inwardly as shown in Fig. 4, and it is not desired therefore to limit the improved device to nozzles of any particular shape or form. The improved device will preferably be of the screw form, but the improved device may be permanently attached to the can as represented in Fig. 5.

The improved device comprises a guard or shell 13 of foraminous material such as perforated metal, as shown in Fig. 1, or wire cloth as shown in Fig. 4, but any suitable foraminous material may be employed for the cage. The apertures or meshes of the cage are sufficiently fine to prevent the passage of flame, but will permit liquids to freely pass.

When the improved device is applied to an outwardly directed threaded nozzle 11, as shown in Fig. 1, the cage 13 is turned over at its upper end and thence directed downwardly with the downwardly directed portion threaded as shown at 14 to engage over the threaded nozzle, and when the cage is applied to an inwardly directed nozzle as shown in Fig. 4, the upper portion of the body of the cage is threaded as shown at 15 to engage the threads of the nozzle and with the upper terminal of the cage directed outwardly in the form of a flange 16 to bear over the upper edge of the can top. When the turned-over form is employed as shown in Fig. 1, a gasket 17 of cork or other like material is inserted between the upper edge of the nozzle and the turned-over portion of the cage, and when the form shown in Fig. 4 is employed the gasket 17 will be inserted between the flange 16 and the body of the can. By this means the joint between the cage and the can is packed and leakage of gas at that point effectually prevented.

When the cage 13 is permanently connected to the can as shown in Fig. 5, of course the gasket 17 will not be required.

A cap device is employed over the upper open end of the cage, and in the construction shown in Fig. 1, the cap comprises a horizontal portion 18 and a threaded depending portion 19 which engages over the

22
 threaded portion 14 of the cage. When the construction shown in Fig. 4 is employed, the threaded portion 19 of the cap engages within the threaded portion 15 of the cage. 5 When the construction shown in Fig. 1 is employed an annular cork packing 20 is inserted between the turned-over upper end of the cage and the lower face of the horizontal portion 18 of the cap, and when the 10 construction shown in Fig. 4 is employed the gasket or packing 20 is inserted between the horizontal portion 18 of the cap and the outturned flange 16 of the cage. The cap is provided with an upwardly directed central rim 21 defining a relatively large central opening through the cap. Bearing upon the upper edge of the rim 21 is the valve of the improved device which comprises a metal disk 22 having a packing of cork or other 20 flexible material 23 which engages the upper edge of the rim 21. The disk 22 is provided with radial "fingers" or projections 24 which are adapted to be bent beneath the outer edges of the packing 23 and thus unite 25 the latter to the disk while at the same time not interfering with its operation as a packing.

Bearing beneath the horizontal portion 18 of the cap is a spring 25, the spring being 30 coupled to the valve member 22 by a chain or other suitable device 26. The chain is preferably connected to the inner end of a wire 27 which extends through the packing 23 and disk 22, and is provided externally 35 of the disk with an eye or ring 28 which serves the twofold purpose of a means for holding the wire in position and likewise provides an effectual lifting member for the valve. By this arrangement it will be obvious 40 that the spring 25 exerts its force to hold the valve yieldably in position in engagement with the rim 21, while at the same time may be lifted free of the rim when a sufficient force is applied either externally 45 by power applied to the ring 28 or by increase of pressure from within the can.

In cans or other containers for gasoline and like hydro-carbons, the gravity being generally low and the temperature of the atmosphere being likewise generally low, causes the vapor in the container above the liquid to condense back into liquid form, and when the container is rapidly moved about as in the case of automobile tanks, 55 the shaking up of the container mixes the air and gases in the upper portion of the container and produces a highly combustible mixture which if ignited bursts the container unless a proper vent or opening is provided, and the improved device herein contained, provides an automatic escape for such dangerous gases through the yieldable valve 22. The spring 25 will be of sufficient strength to retain the valve against

normal pressures, but will readily yield under abnormal or dangerous pressures and thus permit the gases to escape. 65

The improved device is simple in construction, can be inexpensively applied and operates effectually for the purposes described. 70

If the improved device is applied to a can or other container having a pouring nozzle 29, the latter is threaded at its outer end as shown at 30 and provided with a threaded cap 32. In the improved device 75 a supplemental cap is provided having a threaded portion 33 which engages the threaded portion 30 of the nozzle and over which the threaded portion 32 of the cap is disposed, the cap thus serving as a binder 80 to hold the supplemental cap in position. At its center the supplemental cap is directed inwardly in cone shape as shown at 34 and the conical portion perforated. A packing gasket 35 is employed between the 85 two caps as shown. By this simple means when the liquid is to be poured from the can, the outer cap 32 is detached and the liquid permitted to flow through the perforated inner or supplemental cap, the foraminous portion 34 effectually protecting the 90 contents of the can and preventing the ignition of the gases therein while permitting the free flow of the liquid. By this means all of the outlets of the can are provided 95 with effectual safety attachments and all danger of explosions prevented.

Having thus described the invention, what is claimed as new is:

1. In a safety appliance for containers 100 in which the container is provided with a threaded extension, a cage of foraminous material disposed to extend within the container, said cage having a threaded extension disposed parallel and in spaced relation with respect to its body portion, said extension being received on the threaded extension of the container, a cap including a threaded portion which is received on the threaded extension of the cage, said cap 110 being formed with an open end, a plate forming a closure for said open end and movable with respect to the cap, a spring disposed transversely within the cage and supported against movement longitudinally 115 of the cage, and a flexible connection between said spring and said plate, whereby the opening in the cap is normally maintained closed.

2. In a safety appliance for containers, in 120 which the container is provided with a threaded extension, a cage of foraminous material disposed to extend within the container, said cage being formed with a threaded extension, which embraces the cage 125 and which is received by the threaded extension of the container, the extension of the container being formed with an inwardly

disposed flange, there being a packing disposed between said flange and the extension of the cage, a cap provided with a threaded portion received on the extension of the cage, a plate constituting a stop interposed between said cap and the cage, said plate being formed with a central aperture, the cap being provided with an opening which aligns with the aperture formed in the plate, a spring disposed within the cage, said spring being formed with curved extensions which contact with the plate, a plate forming a closure for the cap, and a flexible connection between said second mentioned plate and said spring.

3. In a safety appliance for a container having a threaded extension provided at its upper terminal with an inwardly directed annular flange, a foraminous cage disposed within the extension and extending into the container, a threaded sleeve formed integrally with the cage, said sleeve extending downwardly from the upper end of the cage and being disposed externally thereof and in spaced relation thereto, said sleeve being 25 threaded on the extension; whereby the annular flange thereof is received between the sleeve and the cage, a packing gasket mounted on the flange and held in sealing engagement therewith by the upper terminal of the 30 sleeve, a cap threaded on the sleeve, said cap having an opening formed at its upper terminal, a valve mounted on the upper terminal of the cap, and yieldable means normally holding the valve in sealing position over the opening thereof.

In testimony whereof, I affix my signature in presence of two witnesses.
